INVENTOR.

Charles D. Rogers

UNITED STATES PATENT OFFICE.

CHARLES D. ROGERS, OF PROVIDENCE, RHODE ISLAND, ASSIGNOR TO THE AMERICAN SCREW COMPANY, OF SAME PLACE.

MACHINE FOR GRINDING OR POLISHING THE HEADS OF SCREWS.

SPECIFICATION forming part of Letters Patent No. 253,890, dated February 21, 1882.

Application filed October 12, 1881. (No model.)

To all whom it may concern:

Be it known that I, CHARLES D. ROGERS, of the city and county of Providence, and State of Rhode Island, have invented a new and useful Improvement in Machines for Grinding or Polishing the Heads of Screws; and I do hereby declare that the following specification, taken in connection with the accompanying drawings, forming a part of the same, is a full, clear, and exact description thereof.

My invention relates to a machine for finishing the convex heads of screws and similar articles by grinding, burnishing, or polishing the same.

My improvement consists in a machine embodying a revolving grinding or polishing wheel and a revolving spindle provided with spring or other suitable jaws for holding the work, which spindle is capable of some longitudinal movement in its bearings, and is pivoted so that it can be moved in the arc of a circle in front of the wheel, and is also mounted so that it can be moved radially away from the wheel and swing in the arc of a circle into a position to facilitate the insertion and removal of the work.

Referring to the drawings, Figure 1 represents my improved machine in plan. Fig. 2 shows the same in side elevation. Fig. 3 represents the bed and spindle in the positions they occupy when the work is to be inserted or removed. Fig. 4 shows, in vertical section, the spindle and the parts in and upon which it is mounted.

A is the frame of the machine, upon which the grinding or polishing wheel B is mounted, so that it may be made to revolve by a belt passing over the pulley b. As shown in Fig. 1, the face of the wheel B is provided with one or more peripheral grooves of a contour adapted to the work to be operated upon; but the face of the wheel may be flat, if desired.

To the frame A an arm, A', is adjustably secured, which arm supports a stationary platform, C, adjustably attached thereto.

Upon the platform C the movable bed D and the frame E, which supports the spindle F, are mounted in a manner hereinafter to be described. As shown in Fig. 4, the spindle F is hollow, and its inner end is provided with

spring or other suitable jaws, f, for holding the work. The work shown in the drawings is a round-headed screw, the shank of which is grasped by the jaws f, as shown in the several figures. The spindle F is mounted in the frame E, so that it can be moved longitudinally to and from the wheel B, and it is provided with a pulley, G, splined thereto for giving rotation to the spindle. For the purpose of controlling the longitudinal movements of the spindle and affording a means by which the work can be pressed against the wheel, a disk or button, f', is loosely mounted on the outer end of the spindle, which button is intended to be grasped by the hand of the operator. For the purpose of ejecting the work after it is finished the spindle is provided with an axial spring-punch, g, as shown in Fig. 4.

The spindle-frame E is pivoted to the bed D by a pin, e, so that said frame can swing in the arc of a circle on said bed, in order that all parts of the screw-head may be presented to and be acted upon by the wheel B. The outer face of the bed D is preferably in the form of the arc of a circle, and is provided with stops d d to limit the movements of the spindle-frame.

The longitudinal movement of the spindle F in the frame E is only sufficient to allow the work to be slightly withdrawn from the wheel, and its movements in the arc of a circle are only such in extent as will secure the presentation of all parts of the convex head of the work to the wheel B. It is necessary, therefore, that some means be employed whereby the inner end of the spindle F may be sufficiently withdrawn from the wheel and the spindle may occupy such a position with relation to the wheel as that the work can be conveniently inserted and removed. For this purpose the bed D, to which the spindle-frame is pivoted, is made movable upon the platform C, so that the said bed and the spindle can be moved radially away from the wheel, in order that the spindle may be swung into a position parallel, or nearly so, with the face of the wheel and be sufficiently removed therefrom to allow the work to be conveniently inserted and withdrawn, as shown in Fig. 3.

The manner in which the bed D is mounted on the platform C, so that it may have the movements just described, is as follows: The pin e, which pivots the spindle-frame to the bed D, passes through said bed, and also pivots it to a sliding block, H, which is dovetailed into the platform C. At all times the block H is pressed toward the wheel B by a spring, J, located in a groove in the platform C, and bearing against said platform and a lip, h, on the block H, as shown in Fig. 4.

As shown in each of the figures, the bed D is provided with a handle, D', the inner end of which, as shown in dotted lines, is wedge-shaped or rounded to engage with a recess, e, in the outer edge of the platform—which edge is the arc of a circle—and lock the bed D thereto by the force of the spring J: The rounded inner end of the handle D', in connection with the recess e, forms a stop to limit the inward movement of the bed D and spindle-frame E. By pulling upon the handle D' the block H, the bed D, the frame E, and its spindle may be moved rearward—that is, radially—from the wheel. The bed D may then be moved in the arc of a circle to the right or left, the inner end of the handle D' engaging the edge of the platform C, and the spindle may be moved into the position shown in Fig. 3, in which position the work can be ejected by the spring-punch g, and new work can be readily inserted.

The operation of the machine is substantially as follows: The bed D being locked to the platform C in the position shown in Fig. 1, the spindle F and wheel B being in revolution, and work being in the spindle, the operator seizes the button f' and presses the work upon the wheel, at the same time moving the spindle and its frame from side to side in the arc of a circle until the head of the screw is finished. The handle D' is now seized and the bed D, the spindle, and its frame are moved rearward. The bed D is then swung in the arc of a circle to the position shown in Fig. 3, the inner end of the handle D' bearing upon the edge of the platform, and the spindle is moved to a position parallel, or nearly so, with the face of the wheel. The spring-punch g is now operated to eject the work, a new screw is inserted, the bed D is returned to its original position, and the operations above described are repeated.

From the foregoing description it will be understood that during the operation of finishing the work the bed D and platform C are locked

together, are stationary, and are practically one; but that when the work is to be inserted or removed the bed can be unlocked from the platform, can be moved rearward and in the arc of a circle, thereby withdrawing the work to 60 such a distance from the wheel that the latter will not interfere with the removal and insertion of the work.

As hereinbefore remarked, the platform C is adjustably mounted on the arm A'. This is 65 done in order that the work may be presented to a new surface on the face of the wheel when the latter becomes worn, and the arm A' is also adjustable on the frame of the machine, in order that the work may be brought up to the 70 wheel as the latter becomes reduced in size.

What I claim as my invention, and desire to secure by Letters Patent, is—

1. The combination, as before set forth, of a grinding or polishing wheel, a work-holder 75 which is capable of revolution and longitudinal movement in its bearings, a frame in which said holder is mounted, a sliding block to which said frame is pivoted, and a platform adjustable laterally and longitudinally with relation 80 to the wheel upon which said sliding block is mounted, substantially as and for the purposes specified.

2. The combination, as before set forth, of a grinding or polishing wheel, a work-holder 85 which is capable of revolution and longitudinal movement in its bearings, a frame in which said holder is journaled, a bed, D, upon which said frame is mounted, a sliding block to which said frame and bed are pivoted, a platform for 90 supporting the parts, and suitable means, as described, for temporarily locking the bed to the platform, substantially as set forth.

3. The combination, as before set forth, of a grinding or polishing wheel, a spindle which is 95 capable of revolution and longitudinal movement in its bearings, suitable jaws attached to said spindle for holding the work, a frame in which said spindle is journaled, a bed, D, upon which said frame is mounted, a sliding block 100 to which said frame and bed are pivoted, a spring the pressure of which causes the said parts to move toward the grinding-wheel, and a stop to limit the extent of their forward movement.

CHARLES D. ROGERS.
